UNITED STATES PATENT OFFICE.

WILLIAM B. TRAYNOR, OF CHICAGO, ILLINOIS.

DESIGN FOR A BUTTON OR BADGE.

54,790.

Specification for Design.

Patented Mar. 23, 1920.

Application filed December 30, 1918. Serial No. 269,000. Term of patent 7 years.

To all whom it may concern:

Be it known that I, WILLIAM B. TRAYNOR, a citizen of the United States, residing at Chicago, in the county of Cook and State of Illinois, have invented a new, original, and ornamental Design for a Button or Badge, of which the following is a specification, reference being had to the accompanying drawing, forming a part thereof.

In the drawing:

Fig. 2 shows a side view thereof.

I claim:

The ornamental design for a button or badge, as shown.

WILLIAM B. TRAYNOR.
